(57) **ABSTRACT**

A circuit for generating a reference voltage of bandgap type. The circuit includes a current mirror assembly of cascode type including, from a high supply rail, at least two parallel branches of P-channel MOS transistors. The circuit also includes a bipolar assembly in series with one of the branches of the mirror assembly down to a low supply rail, formed of two parallel branches each including, in series, a diode-connected bipolar transistor and, respectively, one resistor and two resistors. The circuit also includes a differential amplifier for balancing the currents in the two branches of the bipolar assembly, the reference voltage being provided by the terminal of interconnection of the mirror assembly with the bipolar assembly.

**BANDGAP VOLTAGE GENERATOR WITH A
BIPOLAR ASSEMBLY AND A MIRROR
ASSEMBLY**

BACKGROUND OF THE INVENTION

Field of the Invention

The present invention relates to the field of reference voltage generators and, more specifically, to the forming of a bandgap voltage generator. Such a generator is used to generate a reference voltage which is steady in temperature and in supply voltage. The present invention also aims at providing such a reference voltage generator which is not sensitive to possible technological mismatches of the transistors forming it.

Another object of the present invention is to share such a reference voltage generator for the provision of a reference voltage of an analog-to-digital converter and of a voltage depending on the internal temperature of an integrated circuit in which the generator is formed, to form an integrated digital sensor of the internal temperature of a circuit.

SUMMARY OF THE INVENTION

To achieve these and other objects, the present invention provides a circuit for generating a bandgap reference voltage, comprising:

a current mirror assembly of cascode type comprising, from a high supply rail, at least two parallel branches of P-channel MOS transistors;

a bipolar assembly in series with one of said branches of the mirror assembly down to a low supply rail, formed of two parallel branches, each comprising, in series, a diode-connected bipolar transistor and, respectively, one resistor and two resistors; and

a differential amplifier for balancing the currents in the two branches of the bipolar assembly, the reference voltage being provided by the terminal of interconnection of the mirror assembly with the bipolar assembly.

According to an embodiment of the present invention, said mirror assembly comprises:

a first branch formed of two series diode-connected transistors; and

a second branch formed of two transistors in series having their respective gates connected to the respective gates of the two transistors of the first branch, the second branch forming said branch in series with the bipolar assembly.

According to an embodiment of the present invention, the respective inputs of the differential amplifier are connected to the respective branches of the bipolar assembly, its output being connected to the terminal of the first branch of the cascode assembly, opposite to the terminal connected to the high supply rail.

According to an embodiment of the present invention, the four MOS transistors of the cascode assembly have identical sizes.

According to an embodiment of the present invention, the resistor of the first branch of the bipolar assembly is of same value as a first resistor of the second branch which has a common terminal with the resistor of the first branch, the bipolar transistor connected in series with the two resistors being of greater size than the other bipolar transistor.

According to an embodiment of the present invention, the mirror assembly comprises a third branch formed of two P-channel MOS transistors in series with a current-to-

2

voltage conversion resistor between said high and low supply rails, the voltage across said conversion resistor being directly proportional to the internal temperature of the integrated circuit.

5 According to an embodiment of the present invention, the respective gates of these two MOS transistors of the third branch are connected to the respective gates of the two MOS transistors of the first branch.

10 The present invention also provides an integrated digital temperature sensor, comprising:

a circuit for generating a reference voltage and a voltage proportional to the internal temperature;

15 a calibration circuit exploiting the reference voltage and the voltage proportional to temperature, to provide two voltages representative of high and low conversion thresholds, and an analog voltage representing the current temperature; and

20 an analog-to-digital converter receiving the three voltages provided by the calibration circuit, and providing a binary word representative of the internal circuit temperature.

According to an embodiment of the present invention, said voltage representative of the low conversion threshold is formed by the reference voltage.

25 According to an embodiment of the present invention, the output of the analog-to-digital converter is connected to the input of a register for storing the digital temperature.

30 The foregoing objects, features, and advantages of the present invention will be discussed in detail in the following non-limiting description of specific embodiments in connection with the accompanying drawings.

BRIEF DESCRIPTION OF THE DRAWINGS

35 FIG. 1 shows the electric diagram of a voltage generator of bandgap type according to an embodiment of the present invention;

FIG. 2 shows an embodiment of a circuit for activating the voltage generator of FIG. 1; and

40 FIG. 3 schematically shows an embodiment of an integrated digital temperature sensor, using a reference generator such as illustrated in FIG. 1.

DETAILED DESCRIPTION

45 The same elements have been designated with the same reference numerals in the different drawings. For clarity, only those circuit components that are necessary to the understanding of the present invention have been shown in the drawings and will be described hereafter. In particular, the structure of an analog-to-digital converter has not been detailed and may be implemented with any known analog-to-digital converter in its example of application to a digital temperature sensor. Further, the structure of the operational amplifiers has not been detailed, this structure being conventional and within the abilities of those skilled in the art, the present invention being implementable with any conventional type of amplifier.

50 The circuit for generating a reference voltage V_{BG} of bandgap type, illustrated in FIG. 1, comprises a current mirror in a so-called cascode-type assembly comprising two parallel branches each having two P-channel MOS transistors. A first branch comprises two transistors M1 and M3 in series, the source of transistor M1 being connected to a rail 1 of positive supply V_{DD} . Transistors M1 and M3 are diode-connected, their respective gate and drain being interconnected. The second branch comprises two P-channel

3

MOS transistors **M2** and **M4** in series between high supply rail **1** and an output terminal **2** of the circuit providing voltage V_{BG} . The respective gates of transistors **M2** and **M4** are connected to the gates of transistors **M1** and **M3**, respectively. Transistors **M1** and **M2** are mirror-connected, as well as transistors **M3** and **M4**, and transistors **M1** to **M4** all have the same size.

To obtain a stable reference voltage V_{BG} , the respective currents **I1** and **I2** in the two branches of the cascode assembly must be identical. To obtain this identity, an assembly based on diode-connected bipolar transistors between terminal **2** and a rail **3** of reference supply (V_{SS}) is used according to the present invention. This assembly is formed of two parallel branches between terminals **2** and **3**. A first branch comprises a resistor **R1** in series with a PNP-type bipolar transistor **T1**, the emitter of transistor **T1** being connected to resistor **R1**. The second branch comprises the series assembly of two resistors **R2** and **R3** and of a PNP-type bipolar transistor **T2** connected, like transistor **T1**, as a diode, its base and collector being interconnected to rail **3** and its emitter being connected to resistor **R3**. Transistors **T1** and **T2** are selected to have different sizes, transistor **T2** for example having an emitter surface area greater than that of transistor **T1**.

According to the present invention, a differential amplifier **4** is reverse-feedback connected between terminal **2** and drain **5** of transistor **M3**. More specifically, the output of operational amplifier **4** is connected to drain **5** of transistor **M3** while its respective non-inverting and inverting inputs are connected to junction point **6** of resistors **R2** and **R3** and to junction point **7** of resistor **R1** and transistor **T1**.

Finally, the gates of transistors **M1** and **M2** receive an activation voltage V_{GP} , and the inverting input of amplifier **4** receives an activation voltage V_{GN} . Signals V_{GP} and V_{GN} are provided by a circuit which will be described subsequently in relation with FIG. 2. They are used to activate the generator shown in FIG. 1 by properly biasing its transistors.

The operation of the voltage generator of FIG. 1 is the following.

Since transistors **M1** and **M2** have the same gate-source voltage, their respective drain voltages are identical. Currents **I1** and **I2** that they conduct are thus also the same.

Further, since resistors **R1** and **R2** have the same value, the slightest drift between currents **I4** and **I5** running in both branches of the bipolar transistor assembly is compensated for, due to operational amplifier **4**, by a variation in the voltage at node **5**, which balances back currents **I4** and **I5** as being exactly half the value of current **I2**.

As a first approximation, the symmetry between currents **I4** and **I5** only depends on the possible dispersion between resistors **R1** and **R2**.

One may thus write, expressing the respective currents running through transistors **T1** and **T2**:

$$I_s \cdot \exp\left(\frac{q \cdot V_{BE1}}{n \cdot k \cdot T}\right) = A \cdot I_s \cdot \exp\left(\frac{q \cdot V_{BE2}}{n \cdot k \cdot T}\right)$$

where

V_{BE1} and V_{BE2} designate the respective base-emitter voltages of transistors **T1** and **T2**;

q designates the charge of the electron;

k designates Boltzmann's constant;

T designates the circuit temperature;

I_s designates the saturation current of transistors **T1** and **T2**, which are assumed to be identical;

4

A designates the size ratio between transistors **T2** and **T1**; and

n designates the ideality factor of the transistors, which is considered as being identical for transistors formed on a same integrated circuit.

The following can be deduced from the foregoing relation:

$$\Delta V_{BE} = V_{BE1} - V_{BE2} = \frac{n \cdot k \cdot T}{q} \cdot \ln(A).$$

Voltage V_{BG} is then provided by the following relation:

$$V_{BG} = \frac{\Delta V_{BE}}{R3} \cdot RI + V_{BE1}.$$

The reference voltage generator of FIG. 1 effectively is stable in temperature. Indeed, voltage V_{BE1} has, it being a PNP-type transistor, a negative temperature coefficient, that is, it decreases as the temperature increases. However, voltage difference ΔV_{BE} varies proportionally to temperature and with a positive coefficient, that is, it increases along with temperature. Accordingly, the variations compensate for each other in their influence upon voltage V_{BG} .

Further, the provided voltage V_{BG} is stable against possible variations of the supply voltage. Indeed, it is independent from the values of the currents flowing through the assembly branches.

FIG. 2 shows an embodiment of a circuit **10** for activating the MOS transistors of the cascode mirror of FIG. 1 and, more generally, of the different MOS transistor assemblies of the integrated circuit containing the generator of FIG. 1. In particular, operational amplifier **4** of the bandgap generator comprises transistors which are also activated by signals V_{GP} and V_{GN} , as for a conventional circuit.

Circuit **10** comprises a first stage **11** of P-channel MOS transistors and a second stage **12** of N-channel MOS transistors between high **1** and low **3** supply rails. The two stages **11** and **12** receive a same control signal **EN** and each respectively provides voltage V_{GP} and V_{GN} of activation of the transistors of the circuit of FIG. 1.

Stage **11** comprises six P-channel MOS transistors **21** to **26** having their source and their bulk connected to high supply V_{DD} . The gate of transistor **24** and the drain of transistor **25** form the output terminal providing signal V_{GP} of circuit **10**. The drain of transistor **21** is connected to the gate of transistors **23** and **25**. The gate of transistor **21** is connected to the gate of a seventh P-channel MOS transistor **27** series-connected with transistor **22**, its source being connected to the drain and to the gate of diode-connected transistor **22**. The respective gates of transistors **21** and **27** receive signal **EN**. The drains of transistors **23** and **24** are interconnected to the gate of transistor **26** and form a terminal **28** of connection to second stage **12**. The bulk of transistor **27** is connected to high supply V_{DD} . Its drain forms a second terminal **29** of connection to the second stage while the drain of transistor **21** forms a third terminal **30** of connection to the second stage.

Stage **12** of the N-channel transistors comprises five MOS transistors **31** to **35** having all their sources connected to reference supply rail V_{SS} . The gates of transistors **31**, **32**, and **35** are connected to the input terminal providing signal **EN**. The drain of transistor **31** is connected to the drain of transistor **21** (terminal **30**). The gates of transistors **32** and **34** are interconnected to the drains of transistors **33** and **32** (and thus to terminal **29**). The drain of transistor **34** is connected

to terminal 28 while the drain of transistor 35 is connected to the drain of transistor 26 of stage 11 and forms the terminal of provision of output voltage V_{GN} .

In the idle state, when the transistors of the generator of FIG. 1 need not be biased, signal EN is high (for example, at voltage V_{DD}). In this state, transistors 23, 25, 31, 33, and 35 of the circuit of FIG. 2 are on, transistors 21, 22, 24, 26, 27, 32, and 34 being off. As a result, signal V_{GN} is low (voltage V_{SS}) while signal V_{GP} is high. Accordingly, the transistors of the current mirror of FIG. 1 are off.

Upon activation of the circuit by a low setting (to a voltage close to V_{SS}) of input EN, transistors 21, 22, 24, 26, 27, 32, and 34 turn on, while transistors 23, 25, 31, 33, and 35 turn off. In fact, the voltage at initially-discharged node D22 (drain of transistor 22) starts increasing. The same occurs for the voltage at node 29 since no current flows any more through the branch formed of transistors 22, 27, and 32. The turning-on of transistor 34 turns on transistor 26. A current starts flowing from rail 1 to node 7 (FIG. 1). This turns on the mirror-connected transistors of FIG. 1. In steady state, the current flowing through the branch formed of transistors 22, 27, and 32 is identical to the current in the branch formed of transistors 24 and 34 by the mirror assembly of transistors 32 and 34. This current is much smaller than current 12 (FIG. 1). The transistors of the assembly of FIG. 2 are sized so that, in this steady state, the voltage at node 28 is greater than the threshold voltage of transistor 26 to stop the flowing of the starting current to the generator of FIG. 1, which would otherwise adversely affect the operation of its current mirror.

FIG. 3 shows a preferred example of application of the circuit of FIG. 1 to the generation of a reference voltage V_{BG} intended to be used by a circuit 40 for calibrating an analog-to-digital converter 41 (ADC) of an integrated temperature sensor of a circuit.

According to this preferred example, the cascode current mirror of FIG. 1 is also used to provide a voltage V_{TH} depending on the internal temperature of the circuit and more specifically, of the silicon on which it is integrated. For this purpose, a third branch formed of two P-channel MOS transistors M5 and M6 mirror-connected on transistors M1 and M3 is provided, the respective gates of transistors M5 and M6 being connected to the respective gates of transistors M1 and M3. The source of transistor M5 is connected to high supply rail 1 while its drain is connected to the source of transistor M6, the drain of which forms a terminal 42 for providing voltage V_{TH} , connected by a resistor R4 to low supply rail 3.

Since current 13 flowing through the first branch of the assembly is equal to current 12 and resistors R1 and R2 are of same values, current 15 flowing through the second branch of the bipolar assembly is half current 12. One may thus write:

$$I3 = \frac{2 \cdot \Delta V_{BE}}{R3} = \frac{2}{R3} \cdot \frac{n \cdot k \cdot T}{q} \cdot \ln(A)$$

Accordingly, voltage V_{TH} may be written as:

$$V_{TH} = R4 \cdot I3 = \frac{2 \cdot R4}{R3} \cdot \frac{n \cdot k \cdot T}{q} \cdot \ln(A)$$

The only unknown in the above equation is the possible error on ratio R4/R3 with respect to their nominal values. This error can be evaluated as follows:

$$\frac{\Delta \left(\frac{R4}{R3} \right)}{\frac{R4}{R3}} = \frac{\Delta R4}{R4} - \frac{\Delta R3}{R3}.$$

The difference between the error rates on the values of R4 and of R3 can be considered as negligible assuming that both resistors have the same value and the same design (size and pattern on the integrated circuit). The only error source thus is the possible mismatch between resistors.

According to the embodiment of FIG. 3, voltage V_{TH} is intended to be converted by converter 41 to provide a digital word DT representative of the integrated circuit temperature. Word DT is, for example, provided to the data input of a register 43 (TR) for storing this temperature and the clock input of which receives a signal EOC indicative of the end of the conversion, generally present on any analog-to-digital converter. Output OUT of register 43 provides the recorded temperature.

The function of calibration circuit 40 is to amplify signal V_{TH} into an analog signal V_{AT} acceptable at the input of converter 41 and to set two thresholds V_{RLF} and V_{RHF} defining the conversion range of the converter, that is, an analog voltage V_{RLF} for which converter 41 provides a signal DT only comprised of bits at zero and an analog voltage V_{RHF} for which converter 41 only provides bits at one. Low threshold V_{RLF} of converter 41 preferentially corresponds to reference voltage V_{BG} .

Circuit 40 forms, in a way, an analog interface for the inputs of converter 41 so that the low-impedance input of the converter does not affect the measured voltage which must remain temperature-dependent. Levels V_{RLF} and V_{RHF} correspond to the respective possible maximum and minimum levels of analog voltage V_{AT} provided to the converter, that is, B.V_{TH}, where B represent the amplification performed on the measured analog voltage.

In the embodiment of FIG. 3, it is assumed that level V_{BG} directly forms low conversion threshold V_{RLF} of converter 3. Circuit 40 then only adapts the impedance of voltage level 40 V_{BG}, by means of a follower-connected operational amplifier 47 (its inverting input being looped back on output 48) which provides level V_{RLF} , and the non-inverting input of which receives voltage V_{BG} of the measurement circuit.

Threshold V_{RHF} is set, based on voltage V_{BG} , by means 45 of an operational amplifier 49 having a non-inverting input connected to midpoint 50 of a resistive dividing bridge formed of two resistors R6OUT and R6IN in series between output 51 of amplifier 49 and reference supply voltage V_{SS} . Resistances R6IN and R6OUT are adjustable to set the 50 amplification ratio of amplifier 49 and, accordingly, the maximum high conversion level V_{RHF} , in stable fashion with respect to voltage V_{BG} . For impedance matching needs, output 51 of amplifier 49 is connected to the input of a follower-connected operational amplifier 52 which provides 55 threshold V_{RHF} to converter 41, the inverting input of amplifier 52 being connected to its output 53 while its non-inverting input is connected to terminal 51.

As for voltage V_{AT} , it is calibrated by means of an operational amplifier 44 having its inverting input receiving 60 the measured analog level V_{TH} and having its noninverting input connected to the midpoint 45 of a resistive dividing bridge formed of the series association of resistors R5OUT and R5IN between output terminal 46 of amplifier 45 and reference voltage V_{SS} . Terminal 46 forms the output terminal 65 of circuit 40 providing voltage V_{AT} to be converted by converter 41. Resistors R5IN and R5OUT set amplification ratio B.

The calibration of the system by means of circuit 40 consists of submitting the circuit to a temperature corresponding to the minimum threshold (for example, -40°C .) by means of an external cold source. Resistances R5IN and R5OUT are then adjusted for level V_{TH} provided by circuit 40 to correspond to level V_{BG} (that is, level V_{RLF}). This adjustment may be performed either by comparing analog voltages V_{TH} and V_{RLF} , or by reading the output of converter 41, all the bits of which must be at 0 when voltage V_{TH} corresponds to the minimum level of the conversion scale.

The integrated circuit is then submitted to a temperature corresponding to the maximum temperature of the conversion range (for example, $+125^{\circ}\text{C}$), still by means of an external source. Resistances R6IN and R6OUT are then adjusted until voltage V_{RHF} is equal to the measured voltage V_{TH} . Like for the preceding step, either analog levels V_{TH} and V_{RHF} may be compared, or the output of converter 41 may be examined, all its bits then having to be at state 1.

For each of amplifiers 44 and 49, if the output level is too high with respect to the desired level, either the input resistance (R5IN, respectively R6IN) may be increased, or the feedback resistance (R5OUT, respectively R6OUT) may be decreased. If the output level is too low, the inverse operation is performed, that is, the input resistance is decreased or the feedback resistance is decreased.

The analog-to-digital converter used may be any conventional converter providing an output over a number of bits selected according to the resolution desired for the sensor. If need be, the converter inputs/outputs are associated with level-shifting circuits (not shown) for the case where the respective supply voltages of the sensor and of the converter are not compatible with each other.

An advantage of the present invention is that it enables forming a bandgap-type voltage reference generator of simple structure.

Another advantage of the present invention is that the provided generator is particularly well adapted to the generation of a voltage depending on the internal circuit temperature, which can then be converted into a digital word. In this application, the present invention has the advantage of providing a fully-integrated digital temperature sensor.

Of course, the present invention is likely to have various alterations, modifications, and improvements which will readily occur to those skilled in the art. In particular, the choice of the respective sizes of the different transistors as well as of the resistors is within the abilities of those skilled in the art based on the functional indications given hereabove and on the application, especially on the desired temperature operating ranges.

Further, although the present invention has been more specifically described in relation with an example of application to an integrated digital temperature sensor, it more generally applies anywhere a reference voltage stable in temperature and in supply voltage is desired, that is, in any circuit using a bandgap-type voltage. For example, digital-to-analog converters, phase-locked loops (PLLs), etc.

Such alterations, modifications, and improvements are intended to be part of this disclosure, and are intended to be within the spirit and the scope of the present invention. Accordingly, the foregoing description is by way of example only and is not intended to be limiting. The present invention is limited only as defined in the following claims and the equivalents thereto.

What is claimed is:

1. A circuit for generating a bandgap reference voltage, comprising:

a current mirror assembly of cascode type comprising, from a high supply rail, at least two parallel branches of P-channel MOS transistors;

a bipolar assembly in series with one of said branches of the mirror assembly down to a low supply rail, formed of two parallel branches, each comprising, in series, a diode-connected bipolar transistor and, respectively, one resistor and two resistors; and

a differential amplifier for balancing the currents in the two branches of the bipolar assembly, the reference voltage being provided by the terminal of interconnection of the mirror assembly with the bipolar assembly.

2. The circuit of claim 1, wherein said mirror assembly comprises:

a first branch formed of two series diode-connected transistors; and

a second branch formed of two transistors in series having their respective gates connected to the respective gates of the two transistors of the first branch, the second branch forming said branch in series with the bipolar assembly.

3. The circuit of claim 2, wherein the respective inputs of the differential amplifier are connected to the respective branches of the bipolar assembly, its output being connected to the terminal of the first branch of the cascode assembly, opposite to the terminal connected to the high supply rail.

4. The circuit of claim 2, wherein the four MOS transistors of the cascode assembly have identical sizes.

5. The circuit of claim 1, wherein the resistor of the first branch of the bipolar assembly is of same value as a first resistor of the second branch which has a common terminal with the resistor of the first branch, the bipolar transistor connected in series with the two resistors being of greater size than the other bipolar transistor.

6. The circuit of claim 1, wherein the mirror assembly comprises a third branch formed of two P-channel MOS transistors in series with a current-to-voltage conversion resistor between said high and low supply rails, the voltage across said conversion resistor being directly proportional to the internal temperature of the integrated circuit.

7. The circuit of claim 1, wherein the mirror assembly comprises a third branch formed of two P-channel MOS transistors in series with a current-to-voltage conversion resistor between said high and low supply rails, the voltage across said conversion resistor being directly proportional to the internal temperature of the integrated circuit wherein the respective gates of these two MOS transistors of the third branch are connected to the respective gates of the two MOS transistors of the first branch.

8. An integrated digital temperature sensor, comprising: the circuit for generating a reference voltage and a voltage proportional to the internal temperature of claim 6;

a calibration circuit exploiting the reference voltage and the voltage proportional to temperature, to provide two voltages representative of high and low conversion thresholds, and an analog voltage representing the current temperature; and

an analog-to-digital converter receiving the three voltages provided by the calibration circuit, and providing a binary word representative of the internal circuit temperature.

9. The sensor of claim 8, wherein said voltage representative of the low conversion threshold is formed by the reference voltage.

10. The sensor of claim 8, wherein the output of the analog-to-digital converter is connected to the input of a register for storing the digital temperature.

11. A circuit for generating a bandgap reference voltage, comprising:

a current mirror assembly of cascode type comprising at least two parallel branches of MOS transistors;
a bipolar assembly in series with one of the two parallel branches of the mirror assembly; and
a differential amplifier for balancing the currents in the two branches of the bipolar assembly, the reference voltage being provided by a terminal of interconnection of the mirror assembly with the bipolar assembly.

12. The circuit of claim **11**, wherein said mirror assembly comprises:

a first branch formed of two series diode-connected transistors; and
a second branch formed of two transistors in series having their respective gates connected to the respective gates of the two transistors of the first branch, the second branch forming the branch in series with the bipolar assembly.

13. The circuit of claim **12**, wherein respective inputs of the differential amplifier are connected to respective branches of the bipolar assembly, an output of the differential amplifier being connected to the terminal of the first branch of the cascode assembly.

14. The circuit of claim **12**, wherein the four MOS transistors of the cascode assembly have identical sizes.

15. The circuit of claim **11**, wherein a first resistor of the first branch of the bipolar assembly is of a same value as a second resistor of the second branch which has a common terminal with the first resistor of the first branch and a third resistor in series with the second resistor, a second bipolar transistor connected in series with the second and third resistors being of greater size than a first bipolar transistor in series with the first resistor.

16. The circuit of claim **11**, wherein the mirror assembly comprises a third branch formed of two P-channel MOS transistors in series with a current-to-voltage conversion resistor between said high and low supply rails, the voltage across said conversion resistor being directly proportional to the internal temperature of the integrated circuit.

17. The circuit of claim **11**, wherein the mirror assembly comprises a third branch formed of two P-channel MOS transistors in series with a current-to-voltage conversion resistor between said high and low supply rails, the voltage across said conversion resistor being directly proportional to the internal temperature of the integrated circuit wherein the respective gates of these two MOS transistors of the third branch are connected to the respective gates of the two MOS transistors of the first branch.

UNITED STATES PATENT AND TRADEMARK OFFICE
CERTIFICATE OF CORRECTION

PATENT NO. : 6,946,825 B2
DATED : September 20, 2005
INVENTOR(S) : Franck Duclos, Olivier Ladiray and Jérôme Heurtier

Page 1 of 1

It is certified that error appears in the above-identified patent and that said Letters Patent is hereby corrected as shown below:

Column 8.

Line 29, should read:

-- 5. The circuit of claim 1, wherein the resistor of the first --.

Line 43, should read:

-- transistors n series with a current-to-voltage conversion resis --.

Line 46, should read:

-- internal temperature of the integrated circuit wherein the --.

Column 9.

Line 25, should read:

-- internal temperature of the integrated circuit wherein the --.

Signed and Sealed this

Tenth Day of January, 2006

A handwritten signature in black ink, appearing to read "Jon W. Dudas", is placed within a rectangular box with a dotted grid background.
